UNITED STATES PATENT OFFICE.

MAX BREMER, OF NEW BEDFORD, MASSACHUSETTS, ASSIGNOR TO THE PAIRPOINT MANUFACTURING COMPANY, OF SAME PLACE.

DESIGN FOR A HANDLE SOCKET AND PLATE.

SPECIFICATION forming part of Design No. 20,475, dated January 13, 1891.

Application filed August 1, 1890. Serial No. 360,718. Term of patent 14 years.

To all whom it may concern:

Be it known that I, MAX BREMER, of New Bedford, in the county of Bristol and State of Massachusetts, have invented and produced 5 a new and original Design for Handle Sockets and Plates for Burial-Caskets, of which the following is a specification, reference being had to the accompanying drawings, forming part hereof.

10 Figure 1 is a face view of a plate, showing my design. Fig. 2 is an edge view thereof.

15 My design consists in the representation of a cross-shaped tablet forming a surface of a rock which forms a base or support for the tablet.

In the drawings, *a* represents the rock-like

base, and *a'* the cross-shaped tablet forming a surface of the rock, which projects beyond the edges of the smoothed upper surface forming the tablet *a'*. 20

What I claim is—

The design for handle sockets and plates for burial-caskets, the same comprising a base representing rock and a cross-shaped tablet forming the upper surface of the rock, the 25 rock-like base projecting from the edges of the tablet, as set forth.

MAX BREMER.
